PETER COOPER HEWITT, OF RINGWOOD MANOR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

VAPOR-CONVERTER

1,110,549.

Specification of Letters Patent. Patented Sept. 15, 1914.

Original application filed March 20, 1908, Serial No. 422,218. Renewed February 10, 1911, Serial No. 607,874. Divided and this application filed July 19, 1911. Serial No. 639,258.

To all whom it may concern:

Be it known that I, PETER COOPER HEWITT, a citizen of the United States, and resident of Ringwood Manor, county of Passaic, State 5 of New Jersey, have invented certain new and useful Improvements in Vapor-Converters, of which the following is a specification.

Vapor converters or rectifiers capable of rectifying currents of considerable magnitude are well-known and commercially used. 10 Such converters usually consist of glass bulbs having lead wires passing through them and carrying the current to electrodes within the bulbs.

15 To provide converters of larger capacity than those now in commercial use, it is desirable to construct the converter bulbs in such form as to dispense with the requirement for blowing large glass bulbs, and also 20 to dispense with the necessity of passing conducting leads through the glass walls of such bulbs.

It is further desirable to construct the device of such material that the heat generated 25 within the device during its operation may be rapidly and efficiently dissipated or abstracted.

I have devised a converter wherein the cooling of the apparatus may be effected 30 without the employment of large bulbs of glass or similar material and wherein contact leads from outside to inside of the apparatus are unnecessary, different portions of the shell of the apparatus acting as portions 35 of the electrodes.

One convenient form of my invention is shown in the accompanying drawing, which is an elevation of my improved converter.

In this embodiment of the apparatus hold 40 low positive electrodes, 1 and 2, of metal, are illustrated as being connected by bent tubes, 3 and 4, with a metallic receptacle, 5, containing mercury, 6, or other liquid conductor. The mercury may be said to constitute 45 the negative electrode of the converter, while the receptacle, 5, may serve as an easy means of connecting the said electrode with the source of electric current by means of a suitable lead, 30, extending from 50 a binding post, 31, formed on the receptacle.

I prefer to make the bent tubes, 3 and 4, of metal, although they may be of quartz or porcelain.

The electrodes, 1 and 2, are hollow bulbs of iron, copper, aluminum, or other suitable 55 material, having good heat conductivity, and they are connected to the tops of the bent tubes, 3 and 4, respectively, by flange joints, with interposed insulating material, 7, 8. Convenient insulating means are illustrated in detail at the right of the drawing, where insulating rings, 32 and 33, and an insulating tube, 34, serve to protect each of the clamping bolts, 35, 35, from contact with the metal of the flanges, 36 and 37. The 60 same sort of connection may exist between the lower ends of the bent tubes, 3 and 4, and the metallic receptacle, 5, but this latter joint is not always essential, or there may be a number of these joints as the case may 65 require. This receptacle, 5, is also bulbous in shape at its central portion and is provided with tubular extensions by means of which connection is made through insulating flange or other joints, 38 and 39, with 70 the lower ends of the bent tubes, 3 and 4, as already described.

It will be observed that the different parts of the shell or walls of the converter vessel or container form part of the circuit of the 80 converter, the parts, 1 and 2, constituting the positive electrodes and the part 5 being in intimate connection with the negative mercury electrode. When a rectifier is constructed in the manner described herein, 85 there is no necessity for the lead wires being conducted into or through any part of the apparatus, unless the supplemental positive electrode hereinafter to be described should be used, in which case its lead wire can pass 90 through the body of the metallic receptacle, 5, and be insulated therefrom. The leads may simply be connected to the exterior of the bulbs, 1, 2 and 5, say by means of the binding posts, 31, 40 and 41, without passing 95 through or into the apparatus.

The capacity of the rectifier may be varied by varying the size of the several electrodes and the diameter of the connecting tubes. For example, with the positive electrodes, 100 1 and 2, made in the form of hollow bulbs, each having a diameter of six inches, and with the bulbous portion of the metallic receptacle, 5, having a diameter of eight inches, and with connecting tubes each 105 twelve inches long and three inches internal

diameter, a rectifier may be produced having a capacity for handling currents of large quantity, while by substituting for the parts named others having larger diametric measurements, the capacity of the rectifier may be still further increased. These effects may be aided by artificial cooling.

The supplemental positive electrode, 9, may be supported in proximity to the negative electrode, 6, for starting purposes the mode of starting by tilting the apparatus so as to bring these electrodes into contact and then separate them, being now a matter of general knowledge. It also may be started 15 by raising and lowering the negative electrode by the receptacle.

The lead wire, 10, connected with the electrode, 9, may pass through the metallic receptacle, 5, and be insulated therefrom, say 20 by a suitable insulated bushing, 11.

A vacuum pump, 12, may be applied to the device or several bulbs by means of the tubing, 13, 14, provided with insulating joints, 42, 43 and 44. By these means the 25 objectionable vapors generated during the operation of the rectifier may be drawn out by the pump. Inasmuch as the mercury vapor thus drawn out may be needed after condensation in order to replenish the losses 30 at the negative electrode the pump may be discharged through a pipe, 16, into an open receptacle, 17, from which the vapors injurious to the operation of the apparatus 35 may escape, while the condensed mercury vapor may return in the form of mercury through a tube, 18, up into the receptacle, thereby replenishing the losses of the negative electrode, 6. By making the tube, 18, of appropriate length, say 29 inches plus, 40 the upper surface of the mercury may be maintained at the proper height within the receptacle, 5, by atmospheric pressure, and this may be adjusted by movement of the vessel, 17.

The several electrodes may be connected 45 in the usual way to an alternating current source, the anodes or positive electrodes being joined, for instance, to the terminals of a transformer secondary, 19, and the negative electrode being joined through a load 50 circuit, 45, containing translating devices, 46, 46, to an intermediate neutral point, 20, on the said secondary. The primary of the transformer is shown at 21.

At 22 is shown a source of current, the 55 terminals of the source being connected to the lead, 10, and to a binding post, 47, on the wall of the receptacle, 5, which contains the negative electrode, 6.

The tube, 18, may, if desired, be supplied 60 with a check-valve or other valve for preventing the outflow of mercury from the receptacle, 5, such check-valve being illustrated at 48. To cool the apparatus I may 65 make use of any suitable cooling means,

such as an air-blast, 49, or I may use liquid cooling means.

Respecting the structure herein described it will be noted that the sections of the converter or rectifier are insulated from each other and are preferably composed of material having a high heat conductivity, and that the means are supplied for abstracting from the device the heat generated during its operation. Moreover, the positive electrodes are of such material and present such an amount of surface as to cause minimum resistance to the transition of current from the electrode to the vapor, while the negative electrode is of such a character as to 75 permit a change of state or condition necessary at such electrode with but small loss of electric energy and is capable of repairing itself and compensating for such loss, and being continually restored to its original 80 condition by its nature and surroundings. Means for maintaining the negative electrode are shown in the present application. Still further the vapor columns themselves are of such a shape as tend to prevent the 85 danger of short circuiting between any two positive electrodes.

The tubular structure connected with the pump may be crooked, as shown, and of small bore so as to increase the resistance 95 to the passage of current between the electrodes by this path.

This application is a division of my application Serial Number 422,218, filed March 20th, 1908, renewal Serial Number 607,874, filed February 10th, 1911.

I claim as my invention—

1. A rectifier for alternating current, comprising a container having separated parts of good conducting material as the electrodes, and hollow portions of quartz connecting the electrode portions and secured thereto, the whole forming an hermetically sealed container.

2. A mercury vapor apparatus comprising 110 an exhausted container and a liquid cathode therein, said apparatus being exhausted to a high degree of purity, and a relatively long downwardly projecting tubular connection between said cathode and the atmosphere, in combination with means for starting a flow of current in said apparatus, said means including a supplemental anode and means for temporarily raising the level of the cathode into contact with said supplemental anode.

3. A mercury vapor apparatus comprising 115 an exhausted container and a liquid cathode therein, said apparatus being exhausted to a high degree of purity, and a relatively long downwardly projecting tubular connection between said cathode and the atmosphere, in combination with means for starting a flow of current in said apparatus, said means including a supplemental anode and 120

13

means for temporarily raising the level of
the cathode into contact with said supple-
mental anode, said last named means con-
sisting of an open receptacle inclosing one
5 end of said tubular connection to the atmos-
phere.

Signed at New York in the county of

New York and State of New York this 18th
day of July A. D. 1911.

PETER COOPER HEWITT.
